UNITED STATES PATENT OFFICE.

DAVID C. PIERCE, OF NOWRYTOWN, PENNSYLVANIA.

WRENCH.

No. 884,851.

Specification of Letters Patent.

Patented April 14, 1908.

Application filed November 6, 1907. Serial No. 400,925.

To all whom it may concern:

Be it known that I, DAVID C. PIERCE, a citizen of the United States, and a resident of Nowrytown, in the county of Indiana and 5 State of Pennsylvania, have invented certain new and useful Improvements in Wrenches, of which the following is a specification.

This invention is an improvement in wrenches, and consists in certain novel constructions and combinations of parts as will be hereinafter described and claimed.

In the drawing Figure 1 is a side view, and Fig. 2 a longitudinal view partly in section of a wrench embodying my invention. Fig. 3 15 is a detail vertical section on about line 3—3 of Fig. 2. Fig. 4 is an edge view of a portion of the wrench, and Fig. 5 is a detail view illustrating a somewhat different construction in which the stud forming a pivot for the dog is 20 detachably held to the sliding jaw.

The wrench bar A has the handle B, and the fixed jaw C, and the sliding jaw D is movable upon the bar, the latter being provided with ratchet teeth A' for engagement by the 25 pawl of the sliding jaw. The sliding jaw has at its lower end an opening D' to slide upon the wrench bar and has an opening D² at its upper end and is provided at said upper end with a wall D³ which slides along the wrench 30 bar and affords a bearing for one end of a spring E, the other end of which bears against the upper end of the dog F and presses the point F' of the dog into the ratchet teeth of the wrench bar.

35 At its front side the jaw D has an opening D⁴ through which the thumb piece F² of the dog projects and said dog operates within a recess D⁵ in the sliding jaw D. This recess D⁵ opens laterally at one side of the jaw D, 40 and is closed by a cover plate G rabbeted at G' in the side of the recess D⁵ and secured by a screw G², which screws into a stud H projecting from the base wall D⁶ of the recess D⁵. This stud H affords a pivotal support 45 for the dog F, which pivots midway between its ends on the said stud and operates within the recess D⁵, being retained by the cover plate G as will be understood from Figs. 1 and 3 of the drawing.

50 In operation, it will be noticed the spring E forces the jaw into locking engagement

with the locking teeth A', and by pressure upon the thumb piece F² the locking pawl may be released from engagement with the wrench bar so it may be adjusted along the 55 same to any desired position. By removing the cover plate G access may be conveniently had to the dog and its spring for any desired purpose.

In Fig. 3 the pivot stud H is shown integral with the bottom plate of the recess D⁵ for the dog F, while in Fig. 5, the said stud H is made separate from the bottom plate D⁶ of the sliding jaw, and is screwed therein, being provided in its outer end with a nick to 60 receive a screw-driver by which it may be applied and removed.

It will be noticed that the upper end of the dog moves along the curved surface struck on the arc of the circle with the axis of the 65 dog so that the dog is practically in contact at its upper end with the upper end of the sliding jaw and forms a direct connection between the upper end of the sliding jaw and the bearing of the dog against the ratchet 70 teeth of the wrench bar so that the strain upon the wrench jaw is transmitted longitudinally through the dog to the wrench bar in the use of the invention.

I claim—

80 The wrench herein described, comprising a wrench bar having ratchet teeth, a jaw sliding thereon and having a laterally opening recess and a stud projecting from the base wall of said recess and having a threaded 85 socket in its free end, the upper end of said recess being curved on the arc of a circle, a dog pivoted between its ends concentrically with the curved surface and engaging at one end with the ratchet teeth of the wrench bar 90 and moving at its other end along the said curved surface and practically in contact therewith, a spring actuating said dog, a cover plate for the outer end of the laterally opening recesses, and a screw securing said 95 cover plate and threaded in the socket in the free end of the stud, all substantially as and for the purpose set forth.

DAVID C. PIERCE.
